Primary Examiner — Robert A Delehanty(74) Attorney, Agent, or Firm — Leason Ellis LLP(57) CLAIM

The ornamental design for a water tap as shown and described.

DESCRIPTION

1. Water tap

3. Water tap

Fig. 1.1 is a perspective view showing my new design for a water tap;

Fig. 1.2 is a front elevation view thereof;

Fig. 1.3 is a left elevation view thereof;

Fig. 1.4 is a back elevation view thereof;

Fig. 1.5 is a right plan view thereof;

Fig. 1.6 is a top plan view thereof;

Fig. 1.7 bottom plan view thereof;

Fig. 3.1 is a perspective view showing the water tap in condition of use with the removable terminal extended;

Fig. 3.2 is a front elevation view thereof;

Fig. 3.3 is a left elevation view thereof;

Fig. 3.4 is a back elevation view thereof;

Fig. 3.5 is a right plan view thereof;

Fig. 3.6 is a top plan view thereof; and
 Fig. 3.7 bottom plan view thereof.
 The broken lines shown in the drawings represent unclaimed portions of the water tap and forms no part of the claimed design.

1 Claim, 14 Drawing Sheets
